UNITED STATES PATENT OFFICE

143,100

DESIGN FOR A VALVE HANDLE

Jacques Stanitz, Warren, Ohio, assignor to Mullins Manufacturing Corporation, Salem, Ohio, a corporation of New York

Application March 2, 1945, Serial No. 118,220

Term of patent 7 years

(Cl. D91—3)

To all whom it may concern:

Be it known that I, Jacques Stanitz, a citizen of the United States, residing at Warren, in the county of Trumbull and State of Ohio, have invented a new, original, and ornamental Design for Valve Handle, of which the following is a specification, reference being had to the accompanying drawing forming part thereof.

Figure 1 is a top plan view of a valve handle showing my new design; and

Fig. 2 is a side elevation thereof.

I claim:

The ornamental design for a valve handle, substantially as shown.

JACQUES STANITZ.
